[57] CLAIM

The ornamental design for a blade for a garden implement, as shown and described.

DESCRIPTION

FIG. 1 is a top perspective view of a blade for a garden implement showing my new design, with a portion of a handle shown in broken lines for illustrative environmental association purposes only;

FIG. 2 is a bottom perspective view thereof;

FIG. 3 is a side elevational view thereof;

FIG. 4 is a top perspective view of a second embodiment thereof;

FIG. 5 is a bottom perspective view thereof; and

FIG. 6 is an enlarged fragmentary side elevational view of the tip of the blade shown in FIG. 4.
